(57) **CLAIM**

The ornamental design for a web cam, as shown and described.

DESCRIPTION

FIG. 1 is a front perspective view of a web cam showing our new design, with the privacy shutter shown in an open configuration;

FIG. 2 is a front perspective view thereof, shown with the privacy shutter in a closed configuration;

FIG. 3 is a front perspective view thereof, shown with the privacy shutter omitted for ease of illustration;

FIG. 4 is a front elevation view thereof;

FIG. 5 is a rear elevation view thereof;

FIG. 6 is a top plan view thereof;

FIG. 7 is a bottom plan view thereof;

FIG. 8 is a left-side elevation view thereof; and,

FIG. 9 is a right-side elevation view thereof.

The broken lines depict portions of the web cam in which the design is embodied that form no part of the claimed design.
